UNITED STATES PATENT OFFICE.

GEORGE N. JEPSSON, OF WORCESTER, MASSACHUSETTS, ASSIGNOR TO NORTON COMPANY, OF WORCESTER, MASSACHUSETTS, A CORPORATION OF MASSACHUSETTS.

CRUCIBLE.

1,081,535.

Specification of Letters Patent. Patented Dec. 16, 1913.

Application filed August 7, 1911. Serial No. 642,830.

To all whom it may concern:

Be it known that I, GEORGE N. JEPSSON, a citizen of the United States, residing at Worcester, in the county of Worcester and 5 State of Massachusetts, have invented certain new and useful Improvements in Crucibles, of which the following is a specification.

This invention relates to filtering crucibles, filtering or porous dishes, tubes, disks or plates, extraction thimbles, or similar articles, the object of the invention being to provide articles of this character constructed with glazed and unglazed portions 15 or areas, the glazed portion or portions being so completely protected as to prevent all penetration of liquids into the interior thereof.

Heretofore porous tubes and vessels have 20 been partly glazed by dipping or coating, with subsequent firing, but such articles have proven useless for certain purposes requiring complete impenetrability to liquids of the glazed area, as for example in the 25 case of articles intended for quantitative chemical work. The reason for this is that the glaze, particularly when of a refractory character, does not as a rule completely penetrate the wall, but leaves a porous interior layer, into which liquids or suspended 30 materials may freely penetrate and from which it is almost impossible to remove them. According to the present invention the glazed portion is so completely isolated 35 from the unglazed portion as to prevent such penetration, thus making the article suitable for use as a filter or the like for quantitative work.

For a full understanding of the invention, reference is made to the accompanying drawings wherein:

Figure 1 is a central vertical section of a crucible which has been partially glazed by the methods heretofore used; Fig. 2 is 45 a similar view illustrating one step of my method, the upper and lower portions of a porous crucible being shown in separated relation; Fig. 3 is a similar view of a completed crucible in accordance with this invention; Fig. 4 is a similar view of an extraction thimble the upper portion of which has been glazed according to this invention; and Fig. 5 is a detail on a larger scale.

In said drawings, the crucible illustrated in Fig. 1 comprises a porous body

portion 1, to the upper portion of which is applied a glaze 2, which may as indicated at 3 partially penetrate the body, leaving however an interior porous layer 4, into which liquids or fine suspensions may pass 60 freely by capillarity, but from which they cannot be removed by washing. In order to prevent such penetration, it is necessary either that the interstices beneath the glaze shall be completely filled, which is practicable only with very thin walled crucibles and comparatively fluid or highly penetrating glazes; or that an impervious septum or layer should be provided between the glazed and unglazed areas. According to the present invention, the latter course is adopted. 65 To accomplish the desired result I may proceed as follows: The previously formed porous body of the crucible or other vessel or article is first cut, as by a diamond saw or 70 other suitable implement, along the line of demarcation between the part to be glazed and that which is to remain porous. Thus in Fig. 2, the porous body 1 has been cut into upper and lower sections 1^a and 1^b. 75 The section 1^a may now be glazed by any approved method, being completely covered by the glazing composition; the lower or cut edge in particular should be sufficiently coated to form an effective impervious 80 septum or impenetrable layer, as indicated at 5 in Figs. 3 and 4. While the composition is yet sufficiently plastic, the two portions of the crucible are reunited under light pressure, and the whole is then fired in the usual 85 manner. The resulting article presents glazed areas which are completely impenetrable to liquids, owing to the presence of the above described septum and the complete filling of the voids or interstices of 90 this portion of the wall.

The invention is particularly advantageously applied to articles formed of previously molten alumina.

While I have described as a preferred embodiment of my invention a method wherein the article is first formed as a whole, then cut, and one or more of the separated portions glazed before reassembling, it should 100 be understood that in some cases it is practicable to mold or otherwise form the parts of the complete article separately, then to glaze such of these parts as are to be rendered impervious, and finally to assemble the article as herein described. Thus in the 105 110

extraction thimble represented in Fig. 4, the upper or glazed portion 1^a is in form a simple cylinder which may readily be separately molded for attachment to the porous body portion 1^b.

I claim:

1. As a new article of manufacture, a porous crucible or other article having glazed and unglazed portions, said glazed portions isolated from the unglazed portions by a septum of glazing composition.
- 10

2. As a new article of manufacture, a porous container having glazed marginal portions, said glazed portions isolated from the unglazed portions by a septum of glaz- 15 ing composition.

In testimony whereof, I affix my signature in presence of two witnesses.

GEORGE N. JEPPSON.
